Jones, Addington, Ames & Berbold
ATTORNEYS

UNITED STATES PATENT OFFICE.

CHARLES WHITNEY STEVENS, OF CHICAGO, ILLINOIS, ASSIGNOR TO STEVENS PARTITION AND FLOOR DEADENER CO., OF CHICAGO, ILLINOIS, A CORPORATION OF ILLINOIS.

FLOOR CONSTRUCTION.

1,343,234.

Specification of Letters Patent. Patented June 15, 1920.

Application filed March 17, 1917. Serial No. 155,427.

To all whom it may concern:

Be it known that I, CHARLES WHITNEY STEVENS, a citizen of the United States, residing at Chicago, in the county of Cook and 5 State of Illinois, have invented new and useful Improvements in Floor Constructions, of which the following is a full, clear, concise, and exact description, reference being had to the accompanying drawing, forming a 10 part of this specification.

My invention relates to floor constructions.

One of the objects of my invention is to provide an improved form of sound-deadening floor construction. Further objects will 15 appear from the detailed description to follow and from the appended claims.

In the drawings, in which an embodiment of my invention is shown—

20 Figure 1 is a perspective view of part of a room showing my improved floor construction;

25 Fig. 2 is a perspective view of one of the cushioning supporting brackets for the nailings strips; and

Fig. 3 is a fragmentary side elevation of part of the cushioning support.

Referring now to the drawings in detail, the floor construction shown comprises a 30 rough flooring 10 supported by joists underneath it, a plurality of cushioning supports 11 resting on the rough floor 10, a plurality of nailings strips 12 resting on the cushioning supports 11, and a finishing floor 13 secured 35 to and supported by the nailings strips 12.

The cushioning supports are placed about eighteen inches apart along the nailings strips, and the nailings strips themselves are about sixteen inches apart.

40 Each of the cushioning supports 11 comprises a sheet-metal base portion 14 which rests on the rough flooring 10, an L-shaped sheet-metal clip 15 one leg 16 of which is secured to the base 14 by means of rivets 17, 45 and the other leg 18 of which extends upwardly alongside the side face of the nailings strip, and a bent sheet-metal clip 19 having an L-shaped portion 20 shaped to conform to the L-shaped leg 21 of the base 14, and a

portion 22 extending upwardly alongside the 50 other side face of the nailings strip 12. Both side faces of the nailings strip 12 are made to slope downwardly and outwardly, and the upwardly-extending portions 18 and 22 are shaped so as to overhang the sloping 55 side faces of the nailings strip to hold the strip down. This tends to prevent warping of the finishing floor. A pad or cushion 23 of cattle hair, sea grass, or the like, is secured to the support 11. This pad has a 60 horizontal portion 24 between the horizontal sheet-metal portion or leg 16 and the bottom face of the nailings strip, an upwardly-extending portion 24^a between the upwardly-extending sheet-metal portion 18 and one of 65 the sloping side faces of the nailings strip, and an upwardly-extending portion 25 between the upwardly-extending sheet-metal portion 22 and the other sloping side face of the nailings strip. 70

On account of the cushioning supports 11 there is no connection between the finishing flooring 13 and the rough flooring 10 except through the pads 23. The bases 14 are made high enough so that the pipes 26 for the gas 75 and electric wiring can pass beneath the nailings strips 12 without coming in contact therewith.

In constructing the flooring two of the cushioning supports 11 may be placed in 80 position one at each end of the nailings strips, and these supports may be secured to the rough flooring and the nailings strips may be secured to the supports. The intermediate cushioning supports may then be placed in 85 position by slipping the base portion 14 and the horizontal portion 16 of the L-shaped clip 15 underneath the nailings strip with the horizontal portion 24 of the pad 23 between the bottom face of the nailings strip and the 90 horizontal portion 16. The portion 25 of the pad may then be folded up over the side of the nailings strip and the bent clip 19 placed in position. The clip 19 may be secured in 95 position by a headed fastener extending through an opening 27 in the portion 20 of the clip and through a corresponding opening in the base 14.

The sheet metal parts of the support 11 are so shaped that they may be readily formed in dies.

I claim as new and desire to secure by 5 Letters Patent:

1. A floor construction comprising a lower floor, a plurality of cushioning supports bearing on said lower floor, nailing strips supported by said cushioning supports and 10 having their upper faces exposed and lying in a plane above said supports, and a finishing floor secured to said nailing strips, each of said supports comprising a portion overhanging a portion of the nailing strip for 15 holding it down whereby said finishing floor will be restricted to a maximum movement measured by the compression of the cushioning supports.
2. A floor construction comprising a lower 20 floor, a plurality of cushioning supports bearing on said lower floor, nailing strips supported by said cushioning supports and having their upper faces exposed and lying in a plane above said support, and a finishing 25 floor secured to said nailing strips, each of said supports comprising a portion overhanging a portion of the nailing strip for holding it down and cushioning means between said overhanging portion and said 30 nailing strip whereby said finishing floor will be restricted to a maximum movement measured by the compression of the cushioning supports.
3. A floor construction comprising a lower 35 floor, a plurality of cushioning supports bearing on said lower floor, nailing strips supported by said cushioning supports and having their upper faces exposed and lying in a plane above said supports, and a finishing 40 floor secured to said nailing strips, said nailing strips each having an outwardly and downwardly sloping side, and said supports each having a portion overhanging and bearing against said inclined side for holding 45 said nailing strips down whereby said finishing floor will be restricted to a maximum movement measured by the compression of the cushioning supports.
4. A floor construction comprising a lower 50 floor, nailing strips above said lower floor, each nailing strip having both of its side faces sloping downwardly and outwardly, a finishing floor resting upon and secured to said nailing strips, and cushioning means 55 supported by said lower floor for supporting said nailing strips comprising portions overhanging and bearing against both sloping side faces of each of said nailing strips for holding said strips down whereby said nailing 60 strips will be restricted to a maximum movement measured by the compression of the cushioning means.
5. A floor construction comprising a lower 65 floor, nailing strips above said lower floor, each nailing strip having both of its side

faces sloping downwardly and outwardly, a finishing floor resting upon and secured to said nailing strips, and cushioning means supported by said lower floor for supporting said nailing strips comprising portions 70 overhanging and bearing against both sloping side faces of each of said nailing strips for holding said strips down and cushioning means between said overhanging portions and sloping sides whereby said nailing 75 strips will be restricted to a maximum movement measured by the compression of the cushioning means.

6. A floor construction comprising a lower floor, a plurality of cushioning supports 80 bearing on said lower floor, nailing strips supported by said cushioning supports, a finishing floor resting upon and secured to said nailing strips, each of said supports comprising an L-shaped sheet-metal member 85 having a horizontal leg extending underneath the nailing strip and the other leg extending up alongside the side face of the nailing strip, cushioning means between said L-shaped member and the bottom and sides 90 of the nailing strip, and means comprising an interposed cushioning means coöperating with said L-shaped member and its associated cushioning pad to hold said strip down, whereby said strip will be restricted to a 95 maximum movement measured by the compression of the cushioning means.

7. In a building floor construction, the combination with upper and lower floors, of sound insulating means arranged in rows 100 and suitably spaced apart for supporting said upper floor on said lower floor, and non-vibration-transmitting means for anchoring said upper floor to said lower floor, whereby said floor is restricted to a definite prescribed maximum rise.

8. In a building floor construction, the combination with upper and lower floors, of sound-insulating means for supporting said 110 upper floor and nailing strip to said lower floor, said nailing strip having its top face exposed and lying in a plane above said supporting means, and non-vibration-transmitting means for anchoring said nailing strip 115 to said lower floor, whereby said nailing strip will be restricted to a definite prescribed maximum rise.

9. In a building floor construction, the combination with a lower floor, chairs secured to said lower floor, pads or cushions in said chairs, a nailing strip seated on said pads or cushions and having its top face exposed and lying in a plane above said chairs, and an upper floor nailed to said nailing 120 strip of non-vibrating transmitting means for anchoring said nailing strip to said chairs, whereby said nailing strip will be restricted to a definite prescribed maximum 125 rise.

10. A floor construction comprising a lower floor, a plurality of cushioning supports bearing on said lower floor, said supports arranged in rows and suitably spaced apart, nailing strips supported by said cushioning supports, and a finished floor resting upon and secured to said nailing strips, each of said supports comprising a portion over- hanging a portion of the nailing strip for holding it down, whereby said nailing strip will be restricted to a definite prescribed maximum rise.
- 5 In witness whereof, I have hereunto subscribed my name.

CHARLES WHITNEY STEVENS.
